UNITED STATES PATENT OFFICE.

ORSON G. BURCH, OF DETROIT, MICHIGAN.

SASH-REGULATING DEVICE.

Application filed June 24, 1922. Serial No. 570,609.

This invention relates to a sash regulating device and has special reference to that class of devices or mechanisms which are concealed in a door frame, window frame, 5 car body or other structure and employed for raising and lowering a sash, panel, shield or like structure relative to its enclosure. As an instance of such device I may cite an automobile body door which 10 has a sash or transparent panel housed in the lower portion thereof and adapted to be raised and lowered in the door frame. It is to such a device that my invention relates, although the mechanism involved is 15 capable of general use.

The primary object of my invention is to provide a sash regulating device wherein positive and reliable means are employed in a manner as hereinafter set forth for 20 safely raising and lowering a sash and the constructive arrangement of said means is such as to be self locking to the extent of preventing a sash from suddenly lowering after having been raised to an adjusted position. Associated with such means is a novel 25 brake mechanism which will positively prevent a sash from slowly lowering by gravity, therefore my sash raising and lowering device becomes positive in its action of securing a sash against accidental movement.

A further object of my invention is to provide a sash regulating device embodying a guide or rail member in which a traveler is shifted for raising and lowering the sash, 35 the traveler movably engaging the lower edge of the sash so that there will be no binding action between said sash and said travel nor between the vertical edges of the sash and the door frame. A train of gears is employed for actuating the traveler and the inherent tendency of such train of 40 gears to remain stationary eliminates rattling of parts.

A further object of my invention is to 45 provide a traveler and compact sash regulating mechanism that can be easily and quickly installed in a door frame, and the parts of the mechanism are arranged so as to avoid rattling or produce any effects that 50 would be detrimental to the operation of such mechanism in connection with an automobile door.

The above are a few of the objects attained by the construction to be hereinafter

described by aid of the drawings, wherein 55

Figure 1 is an elevation of a conventional form of door frame provided with my sash regulating device;

Fig. 2 is a vertical sectional view of the same;

Fig. 3 is a detail elevation of gear wheels, used in connection with the device;

Fig. 4 is a detail sectional view of the same;

Fig. 5 is an enlarged elevation of a portion of the device;

Fig. 6 is a vertical sectional view taken on the line VI—VI of Fig. 5;

Fig. 7 is a similar view taken on the line VII—VII of Fig. 5;

Fig. 8 is a plan of brake members adapted to form part of the winding arbor of the device;

Fig. 9 is an enlarged cross sectional view of the same, and

Fig. 10 is a bottom plan of the sash regulating devices, partly in horizontal section.

In the drawings, the reference numeral 1 denotes, by the way of an example, a door frame having guideways 2 for the side edges 80 of a sash 3, and this sash may be in the form of a pane of glass having its lower edge provided with a binder or rail 4. The frame 1 has transverse members 5 and 6 in the lower portion thereof and the lower 85 portion of said frame may have inner and outer panels so that a well or compartment 7 will be formed to receive the sash 3 when lowered, thus leaving the upper portion of the frame 1 open.

Suitably secured to the transverse members 5 and 6 is a vertically disposed casing 8 and a wall 9, the casing being in the form of a wide channel having side flanges 10 mounted on the edges of the wall 9. In the 95 wide flat wall of the casing 8 is formed a sinuous or irregular slot 11 extending from the upper end of the casing to the bottom thereof and said slot is composed of semi-circular walls arranged in reverse order so that the walls may be a continuation of one another and thus provide a winding guide slot so that said casing may serve as a guide for a traveler movable lengthwise of the casing.

The traveler comprises two plates 12 and 13 connected by rivets 14 or other fastening means with said rivets serving as pintles for

wheels 15 that roll on the walls of the slot 11. The plates 12 and 13 engage the inner and outer faces of the casing 8 at the marginal edges of the slot 11, as best shown in Figs. 5 and 7 and suitably mounted in the plate 12 is a stepped, flanged or shouldered axle 16 having a roller 17 at one end thereof and a fixed head 18 at the opposite end thereof. Surrounding the axle 16 and bearing against the head 18 is a coiled expansion spring 19 and this spring engages the plate 13 and causes both plates to frictionally engage the casing 8. The expansive force of the spring binding the plate 12 against the inner face of the casing 8 prevents the traveler from accidentally sliding on the guide casing.

Rotatable about the spring 19 is a grooved roller 20 which supports the binder or rail 4 of the sash 3 and may shift back and forth longitudinally of said binder or rail. To prevent accidental displacement of the binder or rail 4 relative to the traveler a guard or hanger 21 is employed and is suitably secured to the binder or rail with the guard of sufficient length to cover the travel of the roller 20 under the sash.

Journalized in the wall 9 and the casing 8 are equally spaced shafts 22 and rotatable on said shafts are gear wheels 23, 24 and 25 affording a train of gears extending from the top of the casing to the bottom thereof and each gear wheel has a set of substantially radially disposed lifting ribs 26, said ribs being arranged or mounted at the marginal portions of the gear wheels and on those faces thereof confronting the guide casing 8 so that said ribs may engage the roller 17 of the traveler and elevate or lower said traveler. The transfer of the traveler from one set of ribs 26 to an adjacent set is accomplished when the sets of ribs vertically align, as shown in Fig. 3, and the outer ends of the ribs are recessed or shaped to provide overlapping tongues 27 which will engage and move the roller 17. Assuming that the gear wheels 24 are rotating in the direction of the arrow Fig. 3, the tongues 27 of the left hand ribs 26 will push the roller in the direction of the arrow, but since the wheels 15 guide the traveler in the slot 11 the tongues 27 will push the traveler upwardly in the slot. The traveler will be elevated by the uppermost gear wheel 24 and eventually pass from under the influence of this gear wheel to the next gear wheel, and so on until the traveler reaches the upper end of the slot 11 at the gear wheel 23. By reference to Figs. 1 and 5 it will be noted that the curved walls of the slot 11 are described on arcs approximating the peripheries of the gear wheels and the reverse arrangement or sinuous contour of the slot walls is necessary on account of some of the gear wheels rotating clock-

wise and others counterclockwise, but irrespective of the direction of rotation the traveler may be shifted from one end of the guide casing to the other and the sash 3 raised or lowered.

At the upper end of the casing 8 is an auxiliary casing 28 and journaled in said casing is a winding arbor 29 on the end of which may be placed a crank or handle 30 for rotating the winding arbor. Loose on the winding arbor 29 is a sleeve 32 provided with short circumferentially disposed slots 33 and extending into said slots are radially disposed pins 34 so that said winding arbor may, at times, shift said sleeve.

About the sleeve 32 are coiled springs 35 and mounted on said sleeve, between the springs 35, is a gear wheel 36 meshing with the gear wheel 23. The springs 35 have end convolutions 37 mounted in the sleeve 32 and other end convolutions 38 extending into the slots 33, these slots being two in number as shown in Figure 8. Fixed in the auxiliary casing 28 about the springs 35 are cylindrical brake members 39 and the inner walls of these members are adapted to be engaged by the convolutions of the springs 35, said springs serving as brake shoes against the brake members to retard rotation of the winding arbor 29 and it is through the medium of the slots 33 that end convolutions of the springs are held so that said springs may be distended against the brake members, also retracted to permit of the winding arbor 29 and the sleeve 32 being rotated without the spring convolutions dragging on the brake member.

The shaft 22 of the gear wheel 25 extends into the spring housing 40 on the wall 9 and in said spring housing is a band spring 41 having one end thereof attached to the housing and the opposite end attached to the shaft 22 of the gear wheel 25. When the gear wheel 25 is rotated by lowering the sash 3 the spring 41 is placed under tension so that its expansive force may be utilized to assist in elevating the sash.

In operation, turning of the winding arbor 29 will coil or retract the springs 35 and through the medium of the gear wheel 36 the train of gears within the guide casing 8 will be placed in operation. The traveler supporting the lower edge of the sash 3 will be raised or lowered with its roller transferred from one gear wheel to others, such transfer taking place when the lifting members 26 align and this is accomplished with practically the same ease as though the traveler were manually lifted by a single hoisting element. When the winding arbor is released the springs 35 expand due to the relative movement between the sleeve 32 and the winding arbor 29 and said springs serving as brake bands hold the winding arbor relative to the brake members 39. It

is obvious that the springs 35 may be rectangular in cross section or otherwise shaped so as to positively grip walls of the brake members 39.

5 When lowering the sash 3 the spring 41 will be wound so that its expansive force may assist in raising the sash, and the constant tendency of this spring to elevate the sash will prevent, in conjunction with the 10 brake mechanism, accidental lowering of the sash. The two last mentioned devices will also contribute to anti-rattling of the raising and lowering mechanism, and while in the drawings there is illustrated a preferred 15 embodiment of my invention, it is to be understood that the structural elements are susceptible to such changes, in size, shape and manner of assembling as fall within the scope of the appended claims.

20 What I claim is:—

1. A sash regulating device comprising a casing, a train of gear wheels in said casing, a traveler supported by said casing and adapted to be shifted by said train of gear 25 wheels and shifted from one gear wheel to another, said traveler engaging the sash to be raised or lowered, and a winding arbor

adapted to be turned to operate the train of gear wheels.

2. A sash regulating device as in claim 1, 30 and means actuated by one of said gear wheels and placed in an active condition to be utilized to assist in raising the sash.

3. A sash regulating device as in claim 1, and a brake associated with said winding 35 arbor and automatically set to hold said winding arbor when released.

4. Means adapted to move a sash, comprising a train of gears, means adapted for setting said train of gears in motion, a set 40 of members on each gear wheel disposed so that during a revolution of the gear wheel the set of members may align with the members of an adjacent gear wheel, a traveler adapted to shift the sash, and means to 45 maintain said traveler in engagement with one set of members so that it may be transferred to an adjacent set of members.

5. Sash moving means as in claim 4, wherein the last mentioned means includes 50 a guide having a sinuous slot therein in which said traveler is movably mounted.

In testimony whereof I affix my signature.
ORSON G. BURCH.
